UNITED STATES PATENT OFFICE.

THOMAS J. HAYES, OF ROSLINDALE, MASSACHUSETTS, ASSIGNOR TO ARBETTER FELLING MACHINE COMPANY, OF BOSTON, MASSACHUSETTS, A CORPORATION OF MAINE.

BLINDSTITCHING-MACHINE FOR FELLING.

1,255,415.

Specification of Letters Patent.

Patented Feb. 5, 1918.

Application filed April 9, 1914. Serial No. 830,789.

To all whom it may concern:

Be it known that I, THOMAS J. HAYES, a citizen of the United States, and resident of Roslindale, county of Suffolk, State of Massachusetts, have invented an Improvement in Blindstitching-Machines for Felling, of which the following description, in connection with the accompanying drawing, is a specification, like characters on the drawing representing like parts.

This invention relates to improvements in machines for doing blind stitching work for felling in which a superimposed layer of fabric is secured to a lower or base layer by means of two parallel lines of stitching, one of which passes through the lower portion of the superimposed fabric without appearing upon the upper surface thereof and the other of which passes through the upper surface of the lower layer of fabric without penetrating its lower surface so that when the stitches are set the line of stitching connecting the two layers of fabric will be substantially or entirely concealed.

This invention comprises means for causing an oscillating movement of a curved needle in a plane parallel to the plane of the work support whereby the needle may be thrust well beneath the edge of the superimposed layer in order to insure the concealment of the line of stitching uniting the upper layer to the base layer of the fabric. It also comprises means for causing the oscillating needle to penetrate and to emerge from the fabric at points in the same plane, which is parallel to the plane of the work support so that the stitches can be laid in the superimposed fabric without distortion of the edge thereof, when the stitch is drawn up.

Another feature of the invention consists in providing means for supporting the oscillating needle rigidly and for vibrating the same laterally to produce parallel rows of stitches in such a manner that there is no likelihood of undesired vibration of the needle which will cause the misplacing of stitches in the fabric.

Other objects of the invention will more fully appear from the following description and accompanying drawings and will be more fully pointed out in the appended claims.

Figure 1 is a side view partly in section of a blind stitch sewing machine embody-

ing one of the preferred forms of my invention.

Fig. 2 is a front view of the sewing machine with the cover plate for the head removed to show the interior thereof.

60

Fig. 3 is a rear view partly in section.

Fig. 4 is a horizontal sectional view taken axially of the sewing machine arm in the plane of the main shaft but showing the main shaft and gears and cams thereon in elevation.

Fig. 5 is a detail side elevation of the needle actuating mechanism and presser foot.

Fig. 6 is a detail front view of the same.

Fig. 7 is a detail plan view of the needle actuating mechanism and presser foot showing the needle in position in which it engages the superimposed layer of fabric in blind stitching.

75

Fig. 8 is a detail plan view showing the needle in the position in which it engages the lower or base layer of the fabric.

The preferred embodiment of my invention illustrated herein comprises a bed plate 80 1, having a suitable work support 2 adjustably arranged relatively thereto, and adapted to be raised and lowered by the usual hand or knee lever, a substantially cylindrical standard 3, and a horizontal arm 85 4 extending from said standard parallel to the bed plate and having at its front end a head 5 inclosing the actuating mechanism for a curved oscillating needle and complementary stitch forming mechanism.

90

The arm 4 is provided with suitable bearings 6, 7 and 8 for the main shaft 10 which is disposed axially of said arm and is provided at the rear end with the usual driving pulley 11 and hand wheel 12 which may be secured thereon in the usual manner. The forward end of the shaft 10 is provided with a spiral gear 13 which engages an idler 14 suitably mounted in the head of the machine and which in turn engages a spiral gear 15 which 100 is secured to the upper end of an annularly disposed shaft 16 which drives the revolving hook or looper. By the use of an intermediate idle spiral gear provision is made for inclosing the shaft 16 and the gear for 105 driving the revolving hook in the head of the machine, the bearing 17 for said shaft preferably projecting inwardly from the side of the head, and the lower bearing 18 being formed in the lower casing of said 110

head. The lower portion of said head is preferably provided with an extension 19 having a journal 20 to adapt it to receive the shaft 21 of the revolving hook or looper 22. A curved cap plate 23 may be secured to said projection to inclose the beveled gears 25 and 26 which are secured respectively to the shafts 16 and 21, and through which rotation is imparted from the shaft 16 to the revolving hook.

In the preferred embodiment of the invention illustrated herein the oscillating needle, which co-operates with the revolving hook, is mounted upon a vertical shaft which is journaled in a sliding support through which the needle is given a lateral or "shogging" movement relative to the line of feed. This mechanism as shown in Figs. 1, 2, and 5 to 8 inclusive comprises a sliding carriage 30 having grooves 31, 32 adapted to engage suitable horizontal ways 33, 34 in the lower portion of the head of the sewing machine. The carriage 30 is preferably provided with upward and downward cylindrical extensions or bosses 35, and 36, these bosses and the carriage being bored to form a journal for a vertical needle shaft 37.

The needle shaft 37 may be provided at its lower end with a collar 38 preferably having an integral lateral and downwardly extending arm, or needle bar 39 slotted and recessed at its end 40 to receive the shank of a curved needle.

The needle shaft 37 may be provided at its upper end with a collar 41 having a laterally extending arm 42 connected to a link 43 which in turn is connected to the arm 44 of a rock shaft 45 mounted in suitable vertically disposed bearings 46 and 47 projecting inwardly from the side of the head, the shaft 45 being provided with an upper arm 48 connected by a ball and socket joint 49 to the arm of a cam strap 50 which embraces a suitable cam 51 carried by the main shaft adjacent to its front end. It will be observed that by the foregoing arrangement the lateral vibration arm 48, caused by the cam 51 oscillates the rock shaft 45, which in turn oscillates the needle shaft 37 and needle 50 to cause the latter to move in a horizontal arcuate path.

A needle guide preferably is provided to steady the needle and prevent vibration or deflection thereof which would result in snagging the fabric. A preferred form of needle guide which is illustrated in Figs. 5, 6, and 8 of the drawing comprises a needle guiding instrumentality 52 preferably forming an integral part of an arm 52* which extends downwardly and laterally from a split collar 53 which is clamped by a set screw 54 upon a boss 36 projecting downwardly from the carriage 30. Inasmuch as this needle guide is carried by the needle bar supporting carriage it partakes of the movement

thereof and with the needle enters beneath the superimposed layer and raises it, thus preventing the needle from catching in the layer before it has reached the position in which it is intended to be thrust into said layer.

The lateral or "shogging" movement is imparted to the needle through a lever 55 which is forked at its lower end to engage a stud 56 projecting laterally from an upstanding ear 57 integral with the carriage 30, the upper end of said lever 55 being pivoted upon a stud 58 projecting inwardly from the side of the sewing machine head. The lever 55 is provided intermediate of its ends with an offset portion 60 carrying a vertical stud 61 having a spherical head 62 seated in a suitable socket in the end of a floating lever 63 which is actuated from a cam 64 preferably carried by a vertical counter shaft 65 driven from the main shaft 10, in the ratio of two to one.

The floating lever 63 is preferably provided with an adjustable section 66 which may be secured thereto by bolts 67 passing through suitable slots in a lever 63, the portion 66 of the lever being provided at its rear end with a yoke 68 which embraces the cam 64.

In order to provide longitudinal movement to reciprocate the carriage for the needle bar, the lever 63—66 is provided with a stud 69 which is pivotally attached to a link 71 which in turn is attached to the end of an arm 70 of a bell crank lever suitably pivoted at its elbow 72 upon a boss 73 extending downwardly from the middle of the sewing machine arm, the pivotal connection at the end of the arm 70 thus forming a movable fulcrum for said lever. The other arm 74 of the bell crank lever is provided with an extension 75 which projects through a suitable slot in the casing of the arm and is provided at its outer end with a milled clamping nut 76. The walls of the slot are preferably made in arcuate form to provide ways 77 against which the milled nut 76 may be clamped to hold the bell crank lever in adjusted position. By the construction above described the fulcrum of the lever 63—66 may be adjusted laterally in respect to the axis of the lever in such a manner as to cause an endwise vibration of said lever which may be varied in proportion to the distance the fulcrum is held from its axis. In operation, the endwise movement of the lever vibrates the depending lever 55 which, being connected to the stud upon the carriage 30 reciprocates the latter and gives a lateral or "shogging" movement to the needle, and the adjustment of the bell crank lever aforesaid provides means for determining the amplitude of the movement of said carriage and for varying the distance between the parallel rows of stitching.

The curved oscillating needle preferably coöperates with a specially formed presser foot which is adapted to accurately guide the superimposed layer of fabric into the path of the needle. In the preferred form of invention illustrated herein the downward extension 19 of the head is provided with a depending shoulder 80 to which the presser foot is secured by suitable screws 82 which pass through the shoulder 80 into sockets 83 in the side of the presser foot (see Fig. 8.)

The presser foot preferably comprises a horizontal base portion 90 having a forward upwardly curved extension or toe 91, the latter being apertured near its junction with the body of the foot to form a throat opening 92 through which the material of the lower layer of fabric may be projected in order that the needle may penetrate the same, and an offset or lateral raised portion 94 extending in a plane parallel to but above the plane of the base portion.

The body portion of the presser foot may be provided on its under surface at one side with a rib 93 to rest upon the lower or base layer of the fabric. The lower surface of the lateral raised portion of the presser foot is preferably disposed in substantially the same plane as the upper surface 95 of the base portion of the presser foot. The offset or web 96 which unites the lower or base portion 90 of the presser foot with the raised portion 94 preferably being cut away at and beyond the throat opening as at 97 to provide a path for the oscillating needle.

In operation the lower or base layer of fabric is fed across the work support in the usual manner. The superimposed layer is introduced at the side of the base portion of the presser foot and passes under the raised portion, the offset forming a guide for the edge thereof. The cut away portion of the web permits the needle, which oscillates in a horizontal plane or in a plane parallel to the work supporting surface of the work support to enter well beneath the superimposed layer of fabric and to enter and emerge from said fabric in the same horizontal plane thus avoiding any rolling of the edge of the superimposed fabric when the stitch is drawn up by the take up, and forming a stitch which will be well concealed when the lines of stitching are completed.

The line of stitching in the lower or base layer of fabric is produced in the usual manner by "shogging" the needle laterally and projecting a portion of the layer of fabric into the path thereof by means of a bender or equivalent mechanism.

The stitch forming mechanism illustrated herein may coöperate with any suitable mechanisms for feeding the material and for bending the lower layer of fabric into the path of the oscillating needle. I have,

however, shown special feeding and bender mechanisms herein but inasmuch as they do not form an essential part of the invention claimed herein it is unnecessary to describe the same in detail herein. It may, however, be stated that the feeding mechanism is preferably actuated from cams 101 and 102 carried by the main shaft in the rear end of the machine which actuate links 103, 104 pivotally connected at their respective lower ends to the arms of rock shafts 105 and 106 which in turn are connected to suitable mechanism at the front end of the machine for raising and lowering, and for advancing and retracting the feed dog 110. 80

The bender mechanism illustrated herein is preferably driven from the vertical counter shaft 65 through a horizontal shaft 120 to which it is connected by beveled gears 121, 122, said shaft 120 being provided at its opposite end with an arm 124 which is connected by a link 125 to an arm 126 of a rock shaft 127 which is disposed in parallelism with shaft 120 but in a plane at one side of the plane of the axis thereof so that the rock shaft 127 is given a differential movement during its rotation.

The shaft 127 in the preferred form of the invention shown herein is provided with a cam 128 which actuates a yoke 129 connected by suitable means with the bender 130. The cam 128 is preferably of a special type adapted to dwell while the bender is in extreme upper position to permit the needle to enter well into the fabric and the differential arrangement between the shafts 127 and 120 is such as to cause a rapid withdrawal of the bender to avoid interference with the operation of the feed mechanism. This, however, forms subject matter of another application and is not therefore a portion of the invention sought to be claimed herein.

Any suitable form of take up mechanism may be utilized in connection with this invention. I have, however, illustrated a convenient type of take up which comprises a bell crank lever 140 pivoted upon a lug 141 on the inner side of the sewing machine arm, one end of the bell crank lever being provided with an offset portion 142 having a thread engaging loop or guide, the other arm 144 of the lever being provided with a stud 145 adapted to enter the slot 146 of a cam 147 suitably secured to the main driving shaft. 120

It is to be understood that the embodiment of the invention shown herein is illustrative merely and is not restrictive and that my invention comprehends any mechanism for oscillating a curved needle in a plane parallel to the plane of the work support and means for giving the needle a lateral or "shogging" movement in the plane in which it oscillates. 130

It is to be understood that the mechanism disclosed herein is illustrative merely and not restrictive, and that this invention may be embodied in other forms within the scope 5 of the following claims.

Having thus described my invention what I claim as new and desire to secure by Letters Patent is:

1. A sewing machine for blind stitching 10 comprising a work support, a curved oscillating needle and complemental stitch forming mechanism, means for feeding the work across the work support and means for presenting the needle with the plane of its oscillation in the penetrating stroke parallel to the work supporting surface of the work support.

2. A sewing machine for blind stitching 20 comprising a work support, a curved oscillating needle and complemental stitch forming mechanism, means for feeding the work across the work support, means for presenting the needle with the plane of its oscillation in the penetrating stroke parallel to the 25 work supporting surface of the work support and with the mean radial line of its arc of oscillation normal to the line of feed.

3. A sewing machine for blind stitching 30 comprising a work support, a curved oscillating needle and complemental stitch forming mechanism, means for feeding the work across the work support, means for presenting the needle with the plane of its oscillation in the penetrating stroke parallel to the 35 work supporting surface of the work support and means for vibrating the needle laterally to produce two rows of stitches whereby the needle while making both of said rows of stitches will oscillate in its penetrating stroke in a plane parallel to the work supporting surface of the work support.

4. In a sewing machine for blind stitching 40 comprising a work support, a curved oscillating needle and complementary stitch forming mechanism located above the work support, means for producing a relatively lateral vibration between the work support and the needle to produce two rows of stitching, means for presenting the needle with 45 its plane of oscillation parallel to the work supporting surface of the work support, and means for holding and directing the edge of the superimposed layer so that the points of penetration and emergence of the needle will 50 be in the same plane parallel to the work supporting surface of the work support.

5. In a sewing machine for blind stitching 55 comprising a work support, a curved oscillating needle and complementary stitch forming mechanism located above the work support, means for producing a relatively lateral vibration between the work support and the needle to produce two rows of stitching, means for presenting the needle with its 60 plane of oscillation parallel to the plane of

the work supporting surface of the work support and means for holding and guiding the edge of the superimposed layer of material at the stitching point, comprising a presser foot having a needle throat, an offset 70 portion adjacent thereto forming an edge guide for the superimposed layer and having a cut away portion to permit the oscillating needle to enter and emerge beneath the upper edge of said superimposed layer.

6. A sewing machine of the class described 75 comprising a work support, a curved oscillating needle and complemental stitch forming mechanism, means for feeding the work across the work support, means for supporting said needle with its plane of oscillation parallel to the work supporting surface of said work support comprising a needle shaft the axis of which is normal to the plane of the work support, a needle bar and needle 80 extending laterally therefrom and means for oscillating said shaft.

7. In a sewing machine for blind stitching 85 comprising a work support, a curved oscillating needle and complemental stitch forming mechanism located above the work support and means for feeding the material over said work support, means for supporting the needle to oscillate in a plane parallel to the plane of the work support, means for 90 vibrating the needle laterally to form two rows of stitches comprising a carriage mounted above the bed plate and movable in a plane parallel thereto, a needle shaft mounted in said carriage in a plane normal 100 to the work supporting surface of the work support and means for actuating said carriage and means for oscillating said shaft.

8. In a sewing machine for blind stitching 105 comprising a work support, a curved oscillating needle and complemental stitch forming mechanism located above the work support and means for feeding the material over said work support, means for supporting the needle to oscillate in a plane parallel to the 110 work supporting surface of the work support, means for vibrating the needle laterally to form two rows of stitches comprising a sliding carriage mounted in ways in the lower portion of the sewing machine head to 115 reciprocate in a plane parallel to the plane of the work support, a shaft journaled in said carriage with its axis normal to the plane of the work support, a needle bar secured to said shaft adjacent to the end 120 thereof, means for oscillating said shaft and means for reciprocating said carriage.

9. In a sewing machine for blind stitching 125 comprising a work support, a curved oscillating needle and complemental stitch forming mechanism located above the work support and means for feeding the material over said work support, means for supporting the needle to oscillate in a plane parallel to the work supporting surface of the work 130

support, means for vibrating the needle laterally to form two rows of stitches comprising a sliding carriage mounted in ways in the lower portion of the sewing machine 5 head to reciprocate in a plane parallel to the plane of the work support, a shaft journaled in said carriage with its axis normal to the plane of the work support, a needle bar secured to said shaft adjacent to the end 10 thereof, means for oscillating said shaft, means for reciprocating said carriage and means for adjusting the amplitude of movement of said reciprocating carriage to vary the distance between the parallel rows of 15 stitching.

10. In a sewing machine for blind stitching comprising a work support, a curved oscillating needle and complemental stitch forming mechanism located above the work 20 support and means for feeding the material over said work support, means for supporting the needle to oscillate in a plane parallel to the work supporting surface of the work support, means for vibrating the needle laterally to form two rows of stitches comprising 25 a sliding carriage mounted in ways in the lower portion of the sewing machine head to reciprocate in a plane parallel to the plane of the work support having a downwardly disposed extension, a needle shaft journaled in said carriage and extension with its axis normal to the plane of the work support, a needle bar and needle secured to 30 said shaft, a needle guide carried by said extension, means for oscillating said needle shaft, and means for reciprocating said carriage whereby the needle guide will serve to steady and direct the needle in both of its 35 penetrating strokes.

Copies of this patent may be obtained for five cents each, by addressing the "Commissioner of Patents, Washington, D. C."

11. In a blind stitch sewing machine for 40 felling a superimposed layer upon a base layer of material comprising a work support, a curved oscillating needle and complemental stitch forming mechanism located above the work support and means for feeding 45 material over said work support, needle actuating mechanism comprising a needle bar, means for supporting the needle bar to permit lateral vibration, means for vibrating said needle bar laterally to form two 50 rows of stitches and a needle guide carried by said needle bar supporting means and movable therewith to enter beneath the superimposed layer and steady and direct the needle during its oscillation. 55

12. In a blind stitch sewing machine for felling a superimposed layer upon a base layer of material comprising a work support and a curved oscillating needle, a complemental stitch forming mechanism located 60 above the work support and means for feeding the same over the work support, needle actuating mechanism comprising a needle bar, a sliding carriage for supporting the needle bar to permit lateral vibration, means 65 for vibrating said carriage laterally and a needle guide carried by said carriage and movable therewith adapted to enter beneath the superimposed layer and steady and direct the needle during its oscillation. 70

In testimony whereof, I have signed my name to this specification, in the presence of two subscribing witnesses.

THOMAS J. HAYES.

Witnesses:
